FLUSH MOUNTED LATCH

Melvin H. Beckman, Rockford, Ill., assignor to Keystone
Consolidated Industries, Inc., Peoria, Ill.

Filed May 11, 1972, Ser. No. 252,537

Term of patent 14 years

Int. Cl. D8—06

U.S. Cl. D8—109

Fig. 1.

Fig. 2.

Fig. 3.

Fig. 4.

Fig. 5.

Fig. 6.

FIG. 1 is a perspective view of a flush mounted latch embodying my new design.

FIG. 2 is a front elevational view thereof;

FIG. 3 is a side elevational view thereof;

FIG. 4 is a rear elevational view thereof;

FIG. 5 is a side elevational view thereof opposite to that of FIG. 3; and

FIG. 6 is a top plan view thereof.

I claim:

The ornamental design for a flush mounted latch, as shown.
